UNITED STATES PATENT OFFICE.

NATHANIEL J. ROGERS, OF TUSCALOOSA, ALABAMA.

PACKING-GUARD FOR JOURNAL-BOXES.

1,113,050.

Specification of Letters Patent.

Patented Oct. 6, 1914.

Application filed February 6, 1914. Serial No. 817,017.

To all whom it may concern:

Be it known that I, NATHANIEL J. ROGERS, a citizen of the United States, residing at Tuscaloosa, in the county of Tuscaloosa and State of Alabama, have invented certain new and useful Improvements in Packing-Guards for Journal-Boxes; and I do hereby declare the following to be a full, clear, and exact description of the invention, such as will enable others skilled in the art to which it appertains to make and use the same.

My invention relates to improvements in journal boxes for railroad cars, and more especially to a packing guard mounted on the interior of said box and adapted to hold the packing in juxtaposition to the journal of the axle, and also to protect the same against accidental displacement, or against intentional removal for improper purposes.

My invention consists of a sheet metal plate held between the wedge and the journal box, and having its outer end projecting downwardly into the said journal box in front of the end of the axle, and holding the packing within a confined area in juxtaposition to the journal of the axle.

This packing guard is so arranged that it cannot be removed without actually cutting away the metal, or without jacking up the car body.

My invention will be understood by reference to the accompanying drawings in which:—

Figure 1 shows a central vertical section through the journal box in the plane of the axis of the axle, the axle and journal being shown in elevation; Fig. 2 shows a section along the line 2—2 of Fig. 1, and looking in the direction of the arrows; and Fig. 3 is a perspective view of the packing guard removed from the journal box.

A represents the car axle having the usual journal A', which projects into the journal box B, whose upper portion B' is connected to the car body in the usual way. The front of this box B is closed with the usual cover C, having the usual spring hinge C', which tends to keep the cover in place.

D represents the brass, and E the wedge which may be of the usual, or any preferred construction.

F represents the packing guard which has the horizontal member F' provided with recesses f adapted to engage corresponding lugs b on the interior of the top B' of the journal box B. This member F' of the

packing guard is held between the wedge E and the top B' of the journal box by the weight of the car, and any possibility of the same from being wedged outward is eliminated by the locking engagement of the recesses f and the lugs b. The front side of the packing guard F is bent downward, as at F², and is provided with holes f' and slots f², both to lighten the metal and for convenience of supplying oil into the space above the packing. The sides F³ of this dependent member F² are flanged inward, and are preferably provided with teeth f³ which hold the packing in place, but yet permit the free passage of the oil around the same. In a similar way the bottom of the dependent member F² is bent inward as at F⁴, and is preferably provided with teeth f⁴ to hold the packing in place and to permit the free passage of the oil between the teeth. Instead of these teeth f³ and f⁴, however, ordinary straight flanges may be used if desired.

The packing G is of any suitable material, such as cotton waste, wool, or other packing which is used in journal boxes, and this packing can be applied to the journal box by shoving it around the sides and beneath the bottom of the dependent member F² of the packing guard. It will thus be held in a confined space in juxtaposition to the journal A' by said packing guard, and cannot expand outward into the front portion of the box where it serves no useful purpose and whence it might be surreptitiously removed by thieves or mischief-makers.

In order to remove the packing, it will be necessary to jack up the car and take out the packing guard, and then remove the packing. It will thus be seen that by this device the packing is held in a confined area, that the place where it is needed does not tend to spread out into the front of the box where it is of no use; and it is also thoroughly protected against surreptitious removal.

It will be obvious that various modifications might be made in the construction of the packing guard, and in the combination and arrangement of parts which could be used without departing from the spirit of my invention.

Having thus described my invention what I claim and desire to secure by Letters Patent of the United States is:—

1. The combination with a journal box and a journal bearing mounted therein of a packing guard made of a piece of bent sheet metal, having its upper member mounted between said journal box and said bearing and held in place by the weight of the car, and having its outer member projecting down in front of the axle and below the lower edge of the same, with means for locking between said upper member to said journal box, substantially as described.
2. The combination with a journal box and a journal bearing mounted therein of a packing guard made of a piece of bent sheet metal, having its upper member mounted between said journal box and said bearing and held in place by the weight of the car, and having its outer member projecting down in front of the axle and below the lower edge of the same, the downwardly-dependent member being provided with flanged edges projecting inwardly, with means for locking said upper member to said journal box, substantially as described.
3. The combination with a journal box and a journal bearing mounted therein of a packing guard made of a piece of bent sheet metal, having its upper member mounted between said journal box and said bearing and held in place by the weight of the car, and having its outer member projecting down in front of the axle and below the lower edge of the same, the downwardly-dependent member being provided with flanged edges projecting inwardly, said inwardly-flanged edges being provided with teeth, with means for locking said upper member to said journal box, substantially as described.
4. The combination with a journal box having downwardly-projecting lugs on the lower side of its top, and a journal bearing mounted therein, of a packing guard made of a piece of bent sheet metal, having its upper member provided with recesses en-

gaging said lugs, said upper member being mounted between said journal box and said bearing and held in place by the weight of the car, and having its outer member projecting down in front of the axle and below the lower edge of the same, substantially as described.

5. The combination with a journal box having downwardly-projecting lugs on the lower side of its top, and a journal bearing mounted therein, of a packing guard made of a piece of bent sheet metal, having its upper member provided with recesses engaging said lugs, said upper member being mounted between said journal box and said bearing and held in place by the weight of the car, and having its outer member projecting down in front of the axle and below the lower edge of the same, the downwardly-dependent member being provided with flanged edges projecting inwardly, substantially as described.

6. The combination with a journal box having downwardly-projecting lugs on the lower side of its top, and a journal bearing mounted therein, of a packing guard made of a piece of bent sheet metal, having its upper member provided with recesses engaging said lugs, said upper member being mounted between said journal box and said bearing and held in place by the weight of the car, and having its outer member projecting down in front of the axle and below the lower edge of the same, the downwardly-dependent member being provided with flanged edges projecting inwardly, said inwardly-flanged edges being provided with teeth, substantially as described.

In testimony whereof I affix my signature in presence of two witnesses.

NATHANIEL J. ROGERS.
